Primary Examiner — Ian Simmons*Assistant Examiner* — Samantha Q Lawrence(74) *Attorney, Agent, or Firm* — Sughrue Mion, PLLC(57) **CLAIM**

The ornamental design for a bus shelter, as shown and described.

DESCRIPTION

FIG. 1 is a front view of a first embodiment of a bus shelter showing our new design;

FIG. 2 is a rear view of the bus shelter;

FIG. 3 is a right side view of the bus shelter;

FIG. 4 is a left side view of the bus shelter;

FIG. 5 is a top view of the bus shelter;

FIG. 6 is a bottom view of the bus shelter;

FIG. 7 is a front perspective view of the bus shelter;

FIG. 8 is a rear perspective view of the bus shelter;

FIG. 9 is a front view of a second embodiment of a bus shelter;

FIG. 10 is a rear view of the bus shelter;

FIG. 11 is a right side view of the bus shelter;

FIG. 12 is a left side view of the bus shelter;

FIG. 13 is a top view of the bus shelter;

FIG. 14 is a bottom view of the bus shelter;

FIG. 15 is a front perspective view of the bus shelter; and,

FIG. 16 is a rear perspective view of the bus shelter.

The broken lines shown in FIGS. 1, 6, 9, 14, and 15 illustrate portions of the bus shelter that form no part of the claimed design.
